UNITED STATES PATENT OFFICE.

CHARLES L. BASTIAN, OF CHICAGO, ILLINOIS.

SIPHON-HEAD.

SPECIFICATION forming part of Letters Patent No. 711,461, dated October 21, 1902.

Application filed October 24, 1901. Serial No. 79,833. (No model.)

To all whom it may concern.

Be it known that I, CHARLES L. BASTIAN, a citizen of the United States, residing at Chicago, in the county of Cook and State of Illinois, have invented certain new and useful Improvements in Siphon-Heads, of which the following is a specification.

This invention relates to novel improvements in heads for siphon-bottles of the general character first disclosed in my application Serial No. 69,510, filed July 24, 1901, which are adapted for use in serving carbonated liquids in the ordinary way and also permit the carbonation of the liquid in the bottle itself instead of in a separate receptacle.

The object of the present invention is to avoid the accidental loss of gas and prevent the escape of any of the carbonated liquid within the bottle while the gas-supply is being turned on and off, and this is accomplished by opening the gas-inlet passage only while the gas-supply is turned on, and a further object of the invention is to utilize the pressure of the gas itself for opening the gas-inlet passage to admit the gas to the bottle, and a still further object of the invention is to provide a valved gas-inlet passage entirely independent of the liquid-outlet passage, whereby the liquid-outlet passage remains closed during the carbonating process and the gas-inlet passage remains closed, except when the gas-supply is turned on for conducting the carbonating process.

In the accompanying drawings I have illustrated a siphon-head in which my novel invention is embodied, and referring thereto—

Figure 1 is a sectional view illustrating the siphon-head ready to have the gas-supply connected therewith. Fig. 2 is a similar view showing the siphon-head in normal position and ready to be operated for serving the carbonated liquid in the bottle. Figs. 3 and 4 are sectional views similar to Figs. 1 and 2, except that the gas-passage terminates above the liquid-valve and the independent valve in the gas-passage is dispensed with.

Referring to the drawings, in which like numerals of reference denote corresponding parts in all of the figures, 10 designates the cap of the siphon-head casing 11, which is internally threaded to engage an external thread

12 on the neck of the bottle 13 or is otherwise adapted to be removably secured upon the bottle, so that the siphon-head can be readily removed for the purpose of filling the bottle or cleaning the same. The body 14 of the casing is bored to form a chamber 15, opening at its upper end and counterbored to form a chamber 16, opening at its lower end in the cap, these two chambers being connected to form a continuous opening throughout the length of the casing. A spout 17 is arranged on one side of the casing and provided with a discharge-passage 18, which communicates with the chamber 16.

A valve 19 is carried by the plug 20 on the end of the stem 21 and is normally held against its seat 22 at the bottom of the chamber 16 by means of a spring 23, which bears at one end against the head 24 of the stem and at the other end against a collar 25, which rests on a shoulder 26 in the casing above the chamber 16. The construction is such that the valve normally closes the liquid-discharge through the chamber 16 and the passage 18 of the siphon-head, and when the valve-stem is depressed to unseat the valve the carbonated liquid within the bottle may be served in a manner common to all siphon-bottles.

The valve-stem is provided with a fluid-passage 27, which in the preferred construction of Figs. 1 and 2 is shown extending throughout its length and opening at its top into a recess 28 in the head of the stem. The lower end of the stem is screwed into the plug 20, which is provided with a valve-chamber 29 and a valve 30, carried by a stem 31 and normally held against its seat 32 by a spring 33. The valve-stem 31 is guided in the block 34, which is provided with an opening to receive the stem and screwed into the lower end of the valve-chamber in the plug, forming also a bearing for the spring 33. The plug is supported by the stem 21 in the upper end of the siphon-tube 35, and it is provided with side openings 36, communicating with the valve-chamber therein.

In the preferred construction of the invention, as shown in Figs. 1 and 2 and just described, the carbonic-acid gas may be introduced through the gas-passage in the stem of the liquid-valve without in any way affecting the liquid-valve, and after the carbona-

tion is complete the liquid may be served by opening the liquid-valve without in any way affecting the gas-inlet valve. In the other construction (illustrated in Figs. 3 and 4) I employ only the liquid-valve 19 and dispense entirely with the independent gas-valve. In this construction the gas-passage 27 in the valve-stem opens through a lateral extension 27' into the chamber 16, and consequently the liquid-valve must be opened before the gas is admitted to the bottle. To prevent the escape of the gas through the discharge-spout when it is being introduced into the bottle for carbonating purposes, I provide a plug 36, which is screwed into the end of the discharge-spout to close the same during the carbonating process, and after the carbonation is complete the plug is removed from the spout and screwed into the recessed head of the valve-stem to close the gas-passage, so that carbonated liquid will not escape therethrough while being served in the ordinary manner and for a further purpose hereinafter described. In the preferred construction of Figs. 1 and 2 it is not necessary to plug the discharge-spout during the carbonating process, as the liquid-valve is not then opened, nor is it necessary to employ this plug for closing the gas-passage, because the gas-valve is not opened when the liquid is being served; but I prefer to use this plug to form a fulcrum for the lever 37, which is connected with a shoulder 38 on the casing by a link 39 and which is employed to depress the valve-stem to open the liquid-valve.

In both the constructions illustrated in the drawings the gas-valve which permits the introduction of gas into the bottle is opened only when the gas is turned on and by the pressure of the gas itself. The head of the liquid-valve stem is located within the chamber 15 and below the top thereof, so that it will not be affected when the siphon-bottle is arranged in the machine employed for agitating the liquid and promoting the carbonating process, such a machine being disclosed in my application, Serial No. 70,769, filed August 3, 1901. It is desirable that the valve through which gas is admitted to the bottle should not be opened until the gas is turned on, so as to avoid loss of gas and pressure and also prevent the carbonated liquid from escaping from the bottle. By utilizing the pressure of the gas itself to open the gas-passage to the bottle the independent gas-valve in the construction of Figs. 1 and 2 and the combined gas and liquid valve in the construction of Figs. 3 and 4 are automatically opened by the outward pressure of the gas and closed by the pressure of the gas within the bottle, assisted by the springs. When the supply of gas is turned off, the gas-passage is immediately closed, thereby preventing the contents of the bottle from accidentally escaping while the bottle is being removed from the carbonating-machine.

In the construction of Figs. 3 and 4 the

combined liquid and gas valve may be opened to admit gas by other means than the pressure of the gas itself, if desired.

70

In practice the siphon-head is removed and the bottle filled with water, after which the siphon-head is replaced and the bottle is arranged in a machine for agitating its contents while carbonic-acid gas is being admitted thereto. If the siphon-head of Figs. 1 and 2 is used, the discharge-spout need not be plugged; but if the siphon-head of Figs. 3 and 4 is used the discharge-spout must be plugged while the gas is being admitted to prevent the gas escaping through the discharge-passage, and this is accomplished by simply changing the plug 36 from its position, closing the gas-passage to the end of the discharge-spout. When the gas is turned on, the pressure thereof will open the independent gas-valve of Figs. 1 and 2 or the combined gas and liquid valve of Figs. 3 and 4, and after the carbonation is complete and the gas turned off the valves of either construction will automatically close, thus confining the carbonated liquid in the bottle. The plug 36 is then arranged in the upper end of the liquid-valve stem, so that the valve can be opened for permitting the discharge of the carbonated liquid in the usual way by applying pressure to the valve-stem through the medium of the lever 37 or other suitable means.

75

My improved siphon-head is not restricted to use with bottles of any character or to use with any particular type of carbonating or charging machine, as it is apparent that gas could be admitted to the siphon head or bottle and its contents agitated in machines of different kinds.

80

Having thus fully described the invention, what I claim, and desire to secure by Letters Patent, is—

85

1. A siphon-head comprising a hollow casing, a discharge-spout, a discharge-valve, a stem for the discharge-valve operating in the casing and provided with a longitudinal inlet-passage, the upper end of said stem being arranged within the hollow casing and adapted for connection with a gas-supply, and a removable plug adapted to be connected with the upper end of the stem.

90

2. A siphon-head comprising a casing having a continuous interior bore opening at the ends of the casing, a discharge-spout, a discharge-valve arranged to close the lower end of said bore, a valve-stem operating in the bore and provided with a longitudinal inlet-passage, an enlarged head for the stem internally threaded and arranged within the bore of the casing, and a threaded plug adapted to be secured in the head of the stem.

95

3. A siphon-head comprising a hollow casing and having a discharge-passage, a valve-stem operating through said casing and provided with an inlet-passage extending from end to end thereof, a plug carried by said stem at its lower end and provided with an

100

interiorly-arranged valve-chamber into which the inlet-passage discharges, a spring-pressed valve within said chamber for closing the lower end of the inlet-passage, and a valve 5 on the upper side of the plug for closing the discharge-passage.

4. A siphon-head comprising a casing provided with an upper chamber and a lower chamber, said chambers communicating with 10 each other and opening respectively at the top and bottom of the casing, a discharge-passage connected with the lower chamber, a valve-stem operating in said chambers and provided with a longitudinal gas-passage, a

valve carried by the lower end of the stem 15 for closing the lower chamber and provided with an interiorly-arranged valve-chamber into which the gas-passage discharges, a spring-pressed valve within said chamber for closing the lower end of the gas-passage, and 20 a head at the upper end of the stem operating within the upper chamber and adapted for connection with a gas-supply.
